UNITED STATES PATENT OFFICE.

NEAL TRIMBLE MCKEE, OF YONKERS, NEW YORK, ASSIGNOR TO LOCOMOTIVE SUPER-HEATER COMPANY, OF NEW YORK, N. Y., A CORPORATION OF DELAWARE.

METHOD OF MAKING PIPE-BENDS.

1,197,299.

Specification of Letters Patent.

Patented Sept. 5, 1916.

Application filed April 10, 1916. Serial No. 90,075.

To all whom it may concern:

Be it known that I, NEAL TRIMBLE MCKEE, a citizen of the United States, residing at Yonkers, New York, have invented certain new and useful Improvements in Methods of Making Pipe-Bends, of which the following is a specification.

My invention relates to pipe-bends, and more particularly to that type of pipe-bends made by the process described in a patent issued jointly to Charles H. True and myself on January 25, 1916, under Number 1,169,209; in which process a die is used, described in a patent issued to us on September 28, 1915, and numbered 1,155,109.

The object of the present invention is to produce an improved pipe-bend of the type referred to, and to make the process of making it easier and more certain.

My invention will be readily understood from the following description taken in connection with the accompanying drawings forming part of the specification and illustrating the preferred form of my invention.

In these drawings—Figure 1 represents a perspective view of the lower half of the female die embodying my improvement; Fig. 2 shows a median vertical section, with portions broken away, of the upper and lower halves of the female die, and the male die, as well as the partly completed pipe bend; Fig. 3 is a plan view of the parts shown in Fig. 2, the upper half of the female die, however, being omitted, and the partially completed pipe-bend being shown in section; Figs. 4 and 5 show a top plan and an end elevation respectively of one of the halves of the female die; Fig. 6 shows in perspective the lower half of a die used in completing the pipe bend; Fig. 7 is a plan view of the same with the uncompleted pipe-bend *in situ* and before the operation of this die has been performed; Fig. 8 is a similar view after the operation; Fig. 9 is a median section of the die, with the bend in position; Fig. 10 is a plan view of the completed bend; and Fig. 11 is a section on line 11—11 of Fig. 10.

The improvement is embodied particularly in the die shown in Figs. 1 to 5, the remaining figures and the description pertaining to them being inserted largely to make clear the relation of the improvement to the later steps in the process.

As will be seen from Figs. 1 to 5, the improved die is identical in most respects with the die hitherto used. It consists essentially of two portions—the female die, comprising the lower half 1 and the upper half 2; and the male member, or “breeches piece”, 3. The latter has not been modified in any way for the present improvement, but is substantially of the form employed in this art for some time past.

The female die has in each of its two halves the usual two, semi-cylindrical, parallel grooves 4, separated from each other by the wall 5 of the usual conformation. The novel feature is the shallow groove or depression 6. In plan this groove is crescent shaped, as shown in Fig. 4, its greatest depth being preferably substantially uniform. The line of greatest depth, 7, runs in general parallel to the two edges 8 and 9 of the groove, being nearer the former, however. From the point of greatest depth the surface slopes up uniformly toward the edges 8 and 9. As indicated in Fig. 2, each half of the female die has a groove such as 80 described, the two lying one directly above the other when the die halves are in place, so that in a plan view the two would coincide.

The die illustrated by Figs. 6 to 9 is used to complete the pipe-bend begun with the die of Figs. 1 to 5. This second die, it will be noted, is essentially of the form used in the past for this step in the process. The depression 12—12—12 is of such form that 90 it gives the completed pipe-bend the desired external shape. The two halves 13 and 13' of the die are symmetrical.

In the operation of the die first described the principal features remain as in the process as hitherto practised. The two pipe ends 10—10 which it is proposed to join are properly heated and placed in position and clamped between the two halves of the female die, whereupon the breeches die 3 is 100 caused by mechanism unnecessary here to describe to perform its movement toward and into the female die and the two pipe ends, slitting the latter, pressing the portions of the pipes adjacent to the slits outward, thereby causing the proper edges to abut and be welded to each other. This, it will be seen, is precisely the process as hitherto practised. The new feature may be described as follows: When the pipe ends are put into 110

the die, they are placed into and clamped in such position that during the operation the shoulder 11 of the breeches die comes into contact with the ends of the pipes before it has quite completed its inward stroke. The consequent endwise pressure causes the metal to be upset and fill the grooves 6. If the pipes are properly placed, the grooves 6 will be just filled by the upset material. The form of the inchoate pipe-bend at this stage is shown particularly in Figs. 3 and 7. It differs from the form obtained by the die of the usual form by having the ridge 14, corresponding to groove 6. The incomplete bend is next placed in the second die 13, as shown in Fig. 7. When so placed the point 15 of the pipe bend coincides with 15' of the edge of the depression in die 13; while the portions 16-16' of the bend protrude a little beyond the points 16'-16' of this edge. The upper die 13' is then brought down by suitable mechanism until it assumes the relative position indicated in Fig. 9, whereby the pipe-bend is given the form indicated in the same figure and in Fig. 8. The bend is then completed by removing the surplus material 17 by suitable means along the curved line 18, and welding the two edges together along the same line by means of an oxy-acetylene flame or other preferred means. The object of thickening the material at the points indicated, by the means described, will now be more readily appreciated. This final weld is made more readily on account of the presence of the extra material, and the weld when made is better. Moreover the thickening of the wall of the bend at this point is of considerable advantage in connection with the use to which these bends have been largely put, *i. e.* the use in superheaters of the smoke-tube type. In these superheaters some of the return bends are in the path of the hot gases which impinge directly on the end of the bend. The improved form given to the pipe-bends by the present method supplies additional resisting power just where it is needed.

Manifestly certain variations may be made in the apparatus and in the method de-

scribed. For example, it may prove desirable, in some cases, to employ an intermediate die, which partly closes the end of the incomplete bend, the die of Figs. 6 to 9 then completing the process. Such variations evidently come within the spirit and are thought to be within the scope of the pending claims.

What I consider as my invention and desire to secure by Letters Patent is:

1. The process of making pipe-bends comprising the steps of suitably heating the pipes to be joined; slitting each of them for a certain distance from the end, pressing the portions adjacent to the slits outward, causing the edges of the portions so bent outward of one of the pipes to abut against the corresponding edges of the other thereby causing a weld, increasing the thickness of the walls over an area adjacent to the end of the finished pipe-bend, and closing the pipe-bend.

2. The process of making pipe-bends comprising the steps of suitably heating the pipes to be joined; simultaneously slitting both of them for a certain distance from the end; simultaneously pressing outward the portions of both adjacent to the slits, thereby causing the corresponding edges of the portions so bent out to abut and become welded; upsetting the material of the walls over an area extending substantially around the incomplete pipe-bend; closing the pipe-bend and removing the material beyond the upset portions.

3. The process of making pipe-bends comprising the simultaneous steps of slitting two suitably heated pipes for a certain distance from their ends, pressing outward the portions of both adjacent to the slits, thereby causing the corresponding edges of these portions to abut and become welded, and upsetting the material of the walls over an area extending substantially around the incomplete pipe-bend; and the steps of closing the pipe-bend and removing the material beyond the upset portions.

NEAL TRIMBLE MCKEE.
